UNITED STATES PATENT OFFICE.

GEORGE G. CHUTE AND CHESTER A. GROAT, OF PORTLAND, OREGON.

ENGINE-STARTER.

1,136,464.

Specification of Letters Patent.

Patented Apr. 20, 1915.

Application filed March 12, 1913. Serial No. 753,868.

To all whom it may concern:

Be it known that we, GEORGE G. CHUTE and CHESTER A. GROAT, citizens of the United States, and residents, respectively, 5 of the city of Portland, county of Multnomah, State of Oregon, have invented a new and useful Improvement in Engine-Starters, of which the following is a specification.

10 Our invention relates to devices whereby an internal combustion engine may be "started" by the application of external force communicated from some remote point.

15 The direct application of our invention concerns self-driving vehicles such as fire, salvage, ambulance and patrol apparatus, where it is necessary that the engine be started as quickly as possible so as to avoid loss 20 of time.

To this end our invention has for its object the providing of suitable and efficient means whereby the engine may be started automatically, in the act of the watchman 25 sounding the alarm gong, or as otherwise convenient, so that the engine will be "warmed up" and the vehicle ready to go the instant the driver of the vehicle is ready.

30 We attain our object by releasably connecting with the crank of the starter-mechanism of the vehicle engine means operated by power communicated from a distant point for turning the crank; and the crank 35 turning means being disengaged from the crank by the energizing of an electro-magnet included in our device, or automatically through the medium of a device operated by the vehicle driving over a member thereof.

40 Our invention further includes the arranging of the power communicating parts so as to accommodate the variations in the 45 position of the vehicle relatively to the location of the power transmitting member of our device to be connected with the engine crank, so as to render it unnecessary to accurately position the vehicle when returned to the station, but the approximate positioning thereof will be sufficient.

50 The details of construction and mode of operation of our invention are fully described in the body of this specification.

In the accompanying drawings: Figure 1 is a side elevation of the devices comprising 55 our invention; in full lines is shown the starter shaft connected with the engine shaft

of the truck, while in broken lines is shown the position assumed by such starter shaft after this connection has been broken. This view further illustrates, diagrammatically, 60 the system of electric wiring and the switch by which such system is controlled; Fig. 2 is a detail showing in side elevation the controlling switch and its electrical connections; this view shows the peculiar construction of the motor-circuit terminal as compared with the other terminals; Fig. 3 is a larger-sized detail, drawn partly in section, 65 illustrating more clearly the construction of the various parts involved therein; this view further shows the action of that portion of our device termed the "unhitcher" and operating to permit the starter shaft to drop relatively downward, as shown in the broken lines of this figure; Fig. 4 is a fragmentary 70 front elevation of the "timing gear" case of a truck, showing a worm-gear attachment adapted to rotate the engine shaft, the latter being shown in section. The panel clutch which prevents the engine shaft from rotating in the wrong direction is shown with its 75 outer face removed, and the starter shaft is shown in operative connection with the worm gear attachment; Fig. 5 is a detail of construction showing means for releasably supporting the starter shaft in its "up" 80 position; the broken lines show such supporting means in their inactive position whereby the starter shaft is allowed to drop to its "down" position; and Fig. 6 is another detail of construction showing how the releasable supporting means referred to in the preceding figure are rendered capable 85 of being released.

The operation of our device will be described in connection with fire apparatus stations. In all such stations, it is customary for each apparatus to be located or "spotted", as it is called, in its own individual place, the position of the apparatus 90 with regard to such place never being varied more than a few inches, and the construction of our device is such as to permit its use notwithstanding such limited variance in the position of the apparatus.

In Fig. 1 is shown the front portion of a truck, *a*, "spotted" in its place on the floor, *b*, of the station. A pair of pedestal blocks, *c*, *c*, fixedly mounted on the plate *c'* of the timing gear-case (see also Fig. 4) rotatably 105 support a worm *d* provided at its lower end with a yoke *e*, which serves as one member

of a universal joint. The member, *f*, of this universal joint is provided with a central square socket for receiving the squared end 20 of the driven shaft 21, to thereby drive the worm. Keyed to the engine shaft *g* is a panel clutch *h*. See Fig. 4. A worm gear, *i*, bears on such panel clutch *h* and when rotated in a clockwise direction will impart to the engine shaft, *g*, a similar rotation. When, however, the engine shaft *g* rotates faster than the worm gear, *i*, is driven, the panel clutch will allow said gear to run freely. The panel clutch *h* is of the well known type of construction. The worm gear, *i*, meshes with and is driven by the worm *d*. The use of a worm drive has this advantage: it prevents the engine from "kicking" back. It is to be noted that the regular form of cranking means, as indicated at *j* in Fig. 1 are not interfered with, and the same may be used at any time independently of the devices used in connection with our invention. Directly beneath the universal joint-member *f* a circular hole *h* is cut in the floor *b*. See Fig. 1. A pendent bracket, *m*, is suspended by its members, *n*, *n* from the floor *b*. A motor *o*, having its shaft provided with a bevel pinion *p*, is supported on such bracket. A cylinder *q* (see also Fig. 3) provided at its lower end with a securing flange *r*, is fixedly bolted to the bracket *m* by the bolts *r'* over a hole *s* in said bracket *m*, in alinement with the hole *k*, of the station floor *b*. Said cylinder *q* is further provided with diametrically opposed holes, *t*, *t*, through which extend the parts, 12 15 later explained. See Figs. 1 and 3. A cylindrical bearing *u*, provided at its lower end with a securing flange *v*, is bolted on the cylinder *q*, the bolting not being seen. The bearing, *u*, is further provided with a pair of diametrically opposed, outwardly projecting studs, *w*, *w* (not seen in Fig. 3) rockably supporting the ring 10 as shown in Fig. 1. A cylindrical box *x* is rotatably journaled in the bearing *u*, the box *x* being supported in place by its flange *y* and a collar *z* threaded on the lower end of the box *x*, as shown in Fig. 3. Said box *x* is further provided with a pair of diametrically opposed, inwardly projecting studs, 2, 2 pivotally supporting the universal joint member 6 on the interior of which are provided studs 7 for pivotally connecting the universal joint member 8 with the member 6. A bevel gear 3 having a hole 4 conforming with the inner periphery of the box *x*, is mounted on the latter by bolts 5. Said bevel gear 3 meshes with and is driven by the bevel pinion *p*, thereby giving the box *x* a rotary motion in the bearing *u*. The joint member 8 is provided with a square bearing hole 9. Arms, 11, 14, extend below the bracket *m* and are made with curved upper extremities, 12 15 which extend through

the holes *t*, of the bearing *q*, and are pivotally connected to the rocket ring 10, by studs 13, 16. A spacing plate 17 is fastened by bolts 17' to the base of the curved arm portions 12 15, as shown in Fig. 3. Said spacing plate is made annular in form, and cored out to accommodate the parts passing through said plate. The lower ends of the arms 11, 14 are made with threaded bolt ends, and a cross arm or bearing 18 is secured on such ends by nuts 19. The arms 11, 14 are thus maintained in parallel position, and provide a bearing for the starter shaft 21 which extends between said arms. This shaft is made with a squared upper portion 20 and a round lower end 21^a. The squared portion 20 slidably bears in the universal joint member 8 and the round end 21^a of said shaft extends through the bearing 18. A disk 22 is pinned to the round portion of the starter shaft 21 by a pin 23. A coil-spring 24 is placed on the shaft 21 between the disk 22 and the universal joint member 8, and a bumper spring 25 is similarly arranged between the disk 22 and the bearing 18.

When the starter shaft is positioned as shown in the full lines of Figs. 1 and 3, its squared end 20 will bear in the central member *f* of the universal joint which is mounted on the truck as mentioned, (see Fig. 1), and the rotation of said starter shaft 21 by the driven gear 3 will drive the worm *d*, thereby the worm gear *i* (as shown in Fig. 4) and thus turn the engine shaft *g*. When, however, the starter shaft is in the position shown in the broken lines of Figs. 1 and 3, its upper squared end will have been withdrawn from the universal joint member *f* of the truck and be so positioned (see Fig. 1) as to be entirely clear of the truck *a*.

Means are provided for releasably supporting the shaft 21 in its "up" position, as shown in Figs. 3, 4 and 5. These means include a latch element and means for releasing of the latch, the devices being arranged as follows: The arm 14 is provided with two pairs of laterally projecting ears 26, in each of which is pivoted a curved arm, 27, by a pin 28. The rear ends of such arms are connected by a coil-spring 29, normally acting to pull the arms apart. Journaled in each arm is a roller 30, which acts as a bearing for the disk 22 when the parts are positioned as shown in the full lines of Figs. 3 and 5. The arm 11 is provided with a pair of laterally projecting portions 31 (see also Fig. 6) having guide slots 32 in which move the rounded extremities 33 of the arms 27. A latch 34 is pivotally mounted on the extremity of one of the arms 27, and is adapted to engage with the extremity of the other arm, for holding the two arms in closed position, as illustrated in the full lines of Fig. 5. By

disengaging the latch 34, the spring 29 will act to swing the arms open and the coil-spring 24 will then force the shaft 21 to start downward. Said shaft will then fall by its own weight till the disk 22 becomes seated on the bumper spring 23. To disengage the latch 34, we make use of an "unhitcher" mechanism similar to that used in fire stations for unhitching horses, unlocking doors, etc. Such "unhitcher" mechanism we arrange as shown in Fig. 3. A plate 35, upon which is mounted the "unhitcher" mechanism, is rigidly mounted on the arm 11 by bolts 36. The plate 35 has perforated lugs 37, supporting two parallel sliding bolts 38. The upper and lower ends of the bolts 38 are connected by cross-bars 44 and 44', on the upper of which is a latch-head 39, positioned between said rods 38. See also bottom portion of Fig. 1. Rigidly secured in the cross-bar 44, between the bolts 38 is a pendent bolt 40, which bears in the brackets 41 and 42, extending laterally from the plate 35. An expansion coil-spring 43 is mounted on the bolt 40 between the bracket 42 and the cross-bar 44, for projecting upward the bolts 38 and therewith the head 39. A plate 47, affixed to the plate 35, supports a pair of electromagnets 48 and a pivoted armature 49. See Fig. 3. Said armature is normally supported by the bifurcated bracket 50, which is mounted on the plate 35 below the plate 47. A bracket 51 made with a central opening for the bolt 40 is mounted on the plate 35, as shown in Fig. 3, and forms a support for the pivoted arm 52, the upper end of which enters the bifurcation of the bracket 50. The lower end of the arm 52 is rounded and bears on the edge of the upper end of the bolt 40. A very light spring 53 mounted on the plate 35, bears against the arm 52 and normally holds the latter outward. When the bolts 38 are down, as shown in the full lines of Fig. 3, the arm 52 will be rotated sufficiently to allow the armature 49 to drop in place behind it, thereby locking said sliding bolts from any upward movement. A cocking lever 54, pivoted on the bracket-arm 42 of the plate 35, has pivotally attached to it an arm 55. The upper end of this arm bears in the bracket arm 41 of the plate 35. A coil-spring 56 connecting the lever 54 and bracket arm 41, normally holds the former in its up position. A draw-head 57, pinned to the arm 55, has a nose 46, which is arranged to enter a recess 45 of the cross bar 44. In order that the pendent mechanism shown in Fig. 3 will hang relatively vertical, a counterweight 14' is provided on the arm 14. It will be seen therefore that when the armature 49 is lifted, by energizing the electromagnets, the upward pressure of the bolt 40 against the lower end of the arm 52 will cause the latter to be moved clockwise on its pivot against the spring 53, thereby permitting the unhitching mechanism to be actuated by the spring 43. In order to reset such mechanism, the cocking lever 54 is pulled down, to engage the draw-head 57 with the cross-bar 44, and thereby pull the actuated devices back to normal position. The spring 53 will simultaneously force the arm 52 outward permitting the armature 49 to drop in behind said arm 52, as shown in Fig. 3, whereupon the unhitching mechanism will be locked against action until such time as the armature is again lifted. It will be observed that the arms 11, 14 are free to swing a limited distance in any direction, such action being permitted by the rocker ring 10, the pivotal connections between the latter and the curved extremities, 12, 15, and the universal joints. In this way, though the truck, α , is not properly "spotted," i. e., moved back into place, our device will accommodate such misplacement, and the connection of the shaft 20 with the universal joint member f is not prevented.

The electrical system by means of which the action of our device is controlled is shown diagrammatically in Figs. 1 and 2. A knife switch 58 has three terminals 59, 60, 61. The main lighting circuit of the station is represented by the wires 62, 63. A series of incandescent lights 64, located in the station house, are connected to the main lighting circuit wires by the wires 65, 66, this auxiliary lighting circuit being normally broken by a knife switch 67. The motor, o , is also energized by the main lighting circuit, as follows: A wire 68 connects one pole of the motor to the wire 62 and a wire 69 connects the other pole of said motor to the knife of the switch 58. A wire 70 connects the terminal 59 to the wire 63. A knife-switch 71, normally closed, lies in this motor circuit, as shown in Fig. 1. The terminal 59 is made of considerable length (see Fig. 2) so that the knife may have a considerable throw without breaking the contact. One pole of a gong 72 is connected to the terminal 60 by a wire 73. The other pole of said gong is connected to the knife of the switch 58 by a wire 74, electro-magnet 78, wire 74', wire 75, battery 76 and wire 77. A rocker armature 79, formed as a bell-crank is so located with respect to the electro-magnet 78 and switch 67, that when the gong circuit is made and said electro-magnet thereby energized, the consequent attraction of the armature 79 will cause the knife-switch 67 of the auxiliary lighting circuit to be closed. The latter circuit will then remain closed until manually broken. The third terminal 61 is connected to one of the electromagnets 48 of the "unhitcher" by a wire 80. The other magnet 48 is connected to the knife of the switch 58 by a wire 81, wire 75, battery 76 and wire 77.

Our device operates as follows: When a call is turned in at the station, the operator on duty throws the knife switch 58 so as to make contact with the terminals 59 and 60. 5 The motor circuit will be closed as follows: wire 62, wire 68, motor *o*, wire 69, terminal 59, wire 70, to wire 63. In this way the motor, *o*, will be energized and the connections therefrom to the truck engine shaft *g* 10 will operate to turn the latter. The gong circuit will be closed through the wire 73, gong 72, wire 74, electro-magnet 78, wire 74', wire 75, battery 76, wire 77, and terminal 60. The consequent closing of the light circuit 15 by the closing of the gong circuit, as previously explained, will cause all of the station lights to be turned on and to remain so until manually turned off. By moving the knife of the switch 58 slightly backward and forward, successive contacts with the terminal 20 60 may be made without breaking the contact with the terminal 59, and the gong may thereby be sounded as many times as desired without breaking the motor circuit. 25 When the gong is no longer to be sounded, the knife of the switch 58 is thrown in an opposite direction till it contacts with the terminal 61. This movement of the knife away from the terminal 59 will break the 30 motor circuit, and the engine shaft *g* will continue to rotate freely, independent of the starting means by virtue of the panel clutch *h*. The contact with the terminal 61 will energize the magnets 48 as follows: 35 wire 80, magnets 48, wire 81, wire 75, battery 76, wire 77 and terminal 61. The consequent attraction of the armature 49 will cause the "unhitcher" mechanism to act as previously described, thereby allowing the starter 40 shaft 21 to fall, and disconnect itself from the truck. As emergency releasing means, we have provided the devices described as follows: A bell-crank 82 hinged to a bracket 83, suspended from the floor *b*, is operable 45 by the depression of a bolt 84. Said bell-crank is held normally in an operative position by the spring 85, the latter causing the bolt 84 to be projected up some distance above the floor through a hole 86 in the lat- 50 ter. A cord 87 connecting with the free leg of the bell-crank runs over pulleys 88 and is fastened to a lug 89 on the armature 49. A spring 90, in this cord, normally holds the cord taut over the pulleys 88. The bolt 84 55 is so positioned that when the truck is "spotted" said bolt will be located directly in the path of one of the front truck wheels. And when the truck is run out it will depress the bolt 84, thereby pulling up on the cord 87, and causing the lifting of the armature 49. This will accomplish the same result as the energizing of the magnets 48, as previously described. Furthermore, a 60 switch 71 in the motor circuit is so located 65 as to be opened by the depression of the bolt

84 simultaneously with the lifting of the armature 49. These emergency releasing means will make the control of the system entirely automatic and altogether independent of the controlling switch 58. It is to be remembered that the shaft 21 is capable of accommodating the forward movement of the truck until dropped out of engagement. It will thus be seen that when an alarm is turned in at a station, the truck engine can be started immediately, so that by the time the driver is ready the engine will be "warmed up" and ready for operating. 70 75

We claim:

1. As a starting mechanism for the engine having a starting element including a crank member and therewith combined gearing for rotating such member, a driven shaft, means for coupling this shaft with said gearing, said coupling means adapted to be disengaged by the longitudinal movement of said driven shaft from said gearing; a rotatable member providing a sliding bearing for said driven shaft; means for supporting the driven shaft in coupled position; and means connecting the rotatable member with a source of power. 80 85 90

2. As a starting mechanism for the engine having a starting element including a crank member and therewith combined gearing for rotating such member, a driven shaft, means for coupling this shaft with said gearing, said coupling means adapted to be disengaged by the longitudinal movement of said driven shaft from said gearing; said coupling means also adapted for accommodating the relative movement of said driven shaft in all directions; a rotatable member providing a sliding bearing for said driven shaft, such sliding bearing adapted to permit the movement of the driven shaft in all directions without interfering with the driving thereof; means for supporting the driven shaft in coupled position; such supporting means controlled by an electromagnet and operable to release the driven shaft by the energizing of the electromagnet; and means connecting the rotatable member with a source of power. 95 100 105 110 115

3. As a starting mechanism for the engine having a starting element including a crank member and therewith combined gearing for rotating such member, a pendent, driven shaft, means for coupling this shaft with said gearing, said coupling means adapted to be disengaged by the longitudinal movement of said driven shaft from said gearing, said coupling means also adapted for accommodating the relative movement of said driven shaft in all directions; a rotatable member and a support therefor, a sliding bearing for said driven shaft, such bearing supported on the rotatable member by means accommodating the movement of said shaft in all directions; means for supporting the 120 125 130

driven pendent shaft in coupled position; such supporting means controlled by an electromagnet and operable to release the driven shaft by the energizing of the electromagnet; and means connecting the rotatable member with a source of power.

4. As a starting mechanism for the engine having a starting element including a crank member and therewith combined gearing for rotating such member, a pendent, driven shaft, means for coupling this shaft with said gearing, said coupling means adapted to be disengaged by the longitudinal movement of said driven shaft from said gearing, 10 said coupling means also adapted for accommodating the relative movement of said driven shaft in all directions; a rotatable member providing a sliding bearing for said driven shaft; such sliding bearing adapted to permit the movement of the driven shaft in all directions without interfering with the driving thereof; a projection on the shaft, pivoted arms engaging with such projection for supporting the 15 driven shaft in coupled position; a spring operating to spread such arms apart in order to release the shaft; a latch holding the arms against the tension of said spring; means for disengaging said latch, such 20 means controlled by an electromagnet; and means connecting the rotatable member with a source of power.

5. As a starting mechanism for the engine having a starting element including a crank member and therewith combined gearing for rotating such member, a pendent, driven shaft, means for coupling this shaft with said gearing, said coupling means adapted to be disengaged by the longitudinal movement of said driven shaft from said gearing, 35 said coupling means also adapted for accommodating the relative movement of said driven shaft in all directions; a rotatable member providing a sliding bearing for said driven shaft; such sliding bearing adapted to permit the movement of the driven shaft in all directions without interfering with the driving thereof; a projection on the shaft, pivoted arms engaging 40 with said projection for supporting the driven shaft in coupled position; a spring operating to spread such arms apart in order to release the shaft; a latch holding the arms against the tension of said spring; 45 a spring actuated projectable device arranged to disengage said latch by impact therewith; means for normally restraining such projectable device, such means controlled by an electromagnet and operated to release the projectable device when the electro-magnet is energized; an electric motor, connections 50 between the same and said rotatable member; a depressible bolt provided in the path over which the vehicle will travel when started; and connections between said depressible bolt and the restraining means of the projectable device adapted to operate the latter and then release the projectable device 55 independently of said electro-magnet, when said bolt is depressed.

6. As a starting mechanism for the engine of a self propelling vehicle, such engine hav-

ing a starting element including a crank member and therewith combined gearing for rotating such member, a driven shaft, means for coupling this shaft with said gearing, said coupling means adapted to be disengaged by the longitudinal movement of said driven shaft from said gearing, said coupling means also adapted for accommodating the relative movement of said driven shaft in all directions; a rotatable member 70 providing a sliding bearing for said driven shaft, such sliding bearing adapted to permit the movement of the driven shaft in all directions without interfering with the driving thereof; means for supporting the driven shaft in coupled position; such supporting means controlled by an electromagnet and operable to release the driven shaft by the energizing of the electromagnet; an electric motor, connections between 75 the same and said rotatable member; a depressible bolt provided in the path over which the vehicle will travel when started; and mechanical means and connections therefrom to said depressible bolt whereby 80 the means supporting the driven shaft in active position are operated, independently of said electromagnet, to release the shaft when the bolt is depressed.

7. As a starting mechanism for the engine of a self propelling vehicle, such engine having a starting element including a crank member and therewith combined gearing for rotating such member, a pendent, driven shaft, means for coupling this shaft with said gearing, said coupling means adapted to be disengaged by the longitudinal movement of said driven shaft from said gearing; a rotatable member providing a sliding bearing for said driven shaft, such sliding bearing adapted to permit the movement of the driven shaft in all directions without interfering with the driving thereof; a projection on the shaft, pivoted arms engaging with such projection for supporting the driven shaft in coupled position; a spring operating to spread such arms apart in order to release the shaft; a latch holding the arms against the tension of said spring; a spring actuated projectable device arranged to disengage said latch by impact therewith; means for normally restraining such projectable device, such means controlled by an electro-magnet and operated to release the projectable device when the electro-magnet is energized; an electric motor, connections between the same and said rotatable member; a depressible bolt provided in the path over which the vehicle will travel when started; and connections between said depressible bolt and the restraining means of the projectable device adapted to operate the latter and then release the projectable device independently of said electro-magnet, when said bolt is depressed.

8. As a starting mechanism for the engine of a self propelling vehicle, such engine having a starting element including a crank member and therewith combined gearing for 5 rotating such member, a pendent, driven shaft, means for coupling this shaft with said gearing, said coupling means adapted to be engaged by the longitudinal movement of said driven shaft from said gearing;
- 10 a rotatable member providing a sliding bearing for said driven shaft, such sliding bearing adapted to permit the movement of the driven shaft in all directions without interfering with the driving thereof; means for 15 supporting the driven pendent shaft in coupled position; such supporting means controlled by an electromagnet and operable to release the driven shaft by the energizing of the electromagnet; an electric motor, connections between the same and said rotatable member; a depressible bolt provided in the path over which the vehicle will travel when started; mechanical means and connections therefrom to said depressible bolt whereby 20 the means supporting the driven shaft in active position are operated, independently of said electromagnet, to release the shaft when the bolt is depressed; and a switch in the circuit of said motor, such switch connected with said bolt and operated by the depression of the latter to break said circuit.
9. In a motion transmitting device the combination of a pendent, driven shaft, a rotatable member and a support therefor, a 25 sliding bearing for said driven shaft, such bearing supported on the rotatable member by means accommodating the movement of said shaft in all directions; means for supporting the driven pendent shaft in active 30 position; and such supporting means controlled by an electromagnet and operable to release the driven shaft by the energizing of the electromagnet.
10. In a motion transmitting device the 35 combination of a pendent, driven shaft, a rotatable member providing a sliding bearing for said driven shaft; a projection on the

shaft, pivoted arms engaging with such projection for supporting the driven shaft in coupled position; a spring operating to spread such arms apart in order to release the shaft; a latch holding the arms against the tension of said spring; and means for disengaging said latch, such means controlled by an electromagnet. 55

11. In a motion transmitting device the combination of a pendent, driven shaft, a rotatable member providing a sliding bearing for said driven shaft; a projection on the shaft, pivoted arms engaging with such 60 projection for supporting the driven shaft in coupled position; a spring operating to spread such arms apart in order to release the shaft; a latch holding the arms against the tension of said spring; a spring actuated 65 projectable device arranged to disengage said latch by impact therewith, and means normally restraining such projectable device, such means controlled by an electromagnet and operated to release the projectable device when the electro-magnet is energized. 70

12. In a motion transmitting device the combination of a movable driven shaft, a rotatable member providing a sliding bearing 75 for said driven shaft, and means for supporting the driven shaft in active position, an electromagnet element included in said supporting means and operating when energized to render said supporting means in- 80 active.

13. In a motion transmitting device, the combination of a movable driven shaft, a rotatable member providing a bearing for said driven shaft, means for placing the 85 driven shaft in active position, and means including and controlled by an electromagnet element for placing the driven shaft in inactive position.
